UTENSIL FACILITATING SNAIL-EATING

Paul Balbo, 76 Village Road S.,
Brooklyn, N.Y. 11223

Filed Sept. 26, 1973, Ser. No. 400,727

Term of patent 14 years

Int. Cl. D7—01

U.S. Cl. D7—7

FIG. 1

FIG. 2

FIG. 3

FIG. 4

FIG. 5

FIG. 1 is a top perspective view of a utensil facilitating snail-eating showing my new design;

FIG. 2 is a top plan view thereof;

FIG. 3 is a bottom plan view thereof;

FIG. 4 is a side elevational view thereof; and

FIG. 5 is a sectional view thereof taken on the plane of line 5—5 of FIG. 2.

I claim:

The ornamental design for a utensil facilitating snail-eating, as shown.
